UNITED STATES PATENT OFFICE.

CHARLES L. BELLAMY, OF ARLINGTON, NEW JERSEY.

CLAMP AND VISE.

SPECIFICATION forming part of Letters Patent No. 286,376, dated October 9, 1883.

Application filed July 2, 1883. (No model.)

To all whom it may concern:

Be it known that I, CHARLES L. BELLAMY, of Arlington, Hudson county, New Jersey, have invented certain new and useful Improvements in Clamps and Vises, of which the following is a specification.

My invention applies to the ordinary wood-worker's or cabinet-maker's bench-clamp, which is affixed to the front of the bench, and usually consists of two broad clamp-plates forced together by a screw, the upper edge of the jaws terminating on a level with the top of the bench; and the object of my invention is to combine ordinary vise-jaws for metal-working with the said clamp-jaws in such manner that the vise-jaws may be easily removed or applied, as occasion requires, thus forming a compound clamp or vise adapted either for wood or metal work without at all impairing the ordinary functions of the clamp, and thereby producing a more useful tool for the shop.

My invention may therefore be briefly stated to consist in the combination, with the bench clamp-jaws, of separable vise-jaws adapted to be affixed to and removed from the clamp-jaws, as occasion requires, and also in certain special constructions of the parts, as herein-after fully set forth.

In the annexed drawings, Figure 1 presents a longitudinal section of my improved clamp and vise, and Fig. 2 is a front elevation thereof. Fig. 3 is a plan view, with the edge of the bench in section; and Fig. 4 is a plan of the clamp detached from the bench and having the vise-jaws removed.

In Figs. 1 and 3, *a* indicates the front plank or edge of the bench to which the bench-clamp is affixed.

b c indicate the two jaws of the bench-clamp, which are formed, as usual, of two broad cast-metal plates of rectangular form, one of which, *b*, is fixed to the front of the bench, while the other, *c*, is movable to or from the former, in the usual manner. The fixed plate *b* is formed with two countersunk screw-holes at each end, to admit screws *d d*, (see Fig. 3,) whereby it is fastened to the bench, as usual. This fixed plate has also two tubular lugs or sleeves, *i*, projecting backward therefrom, which admit two parallel guide-rod, *kk*, which project from

the movable plate *c*, and thus support and guide the movable plate in its motions to or from the fixed plate. Through the center of both plates the strong clamp-screw *e* passes, its outer end being fastened in the hub of a hand-wheel, *l*, which bears upon the front of the movable plate *c*, while the rim of the wheel stands sufficiently out from the plate to admit the ready grasp of the hands for turning the screw in or out, and thus opening or closing the clamp. The inner end of the screw works through a nut, *f*, which is held between two projections, *g g*, on the back of the fixed plate, which prevent it from turning, and as the nut is thus confined between said projections in a recess in the face of the bench when the plate is screwed up to the same, it follows that the turning of the screw in the nut will cause the movable camp-plate to forcibly approach to or recede from the fixed plate in the ordinary manner. The top edge of the plates *b c* are, as usual, placed on a level with the top of the bench, and the inner faces of the plates are planed smooth and level, so as to clamp a board or other wooden piece between them true and firm, in the usual manner of a wood-worker's clamp.

Now, in order to enable metal-work or wood-work to be held and worked in the clamp, I combine with the clamp-jaws a set of movable vise-jaws, *m m'*, which may be affixed to or removed from the clamp-jaws, as occasion requires, without affecting the rest of the clamp. These vise-jaws *m m'* are of the usual overhanging shape of vise-jaws, and are formed with a flat base which seats on the top edge of the clamp-plates, or rather on the top of a semi-cylindrical swell or boss, *t*, formed on the top of the plates, over the clamp-screw *e*, which swells are bored with a simple round hole, *t'*, forming sockets, in which a cylindrical stem, *u*, projecting from the base of the vise-jaws, is received and firmly socketed, thus holding the vise-jaw in a rigid manner to the clamp-jaw, yet admitting of its easy removal or fixation, as required.

The vise-jaw *m'*, which is socketed in the fixed clamp-plate *b*, is prevented from turning in its socket by means of a small pin, *o*, which projects from the socketing-stem, and fits into

a notch or groove, *p*, in the top of the socket, while the other jaw, *m*, on the movable clamp-plate, is provided with a movable locking-pin, *r*, which may be passed through a hole in 5 the front of the socket into a coinciding hole in the stem of the vise-jaw, so as to hold said jaw parallel with the first, and thus adapt the vise for holding parallel work; whereas, if it is desired to hold beveled work, it is only necessary to remove the locking-pin, which will 10 leave the jaw free to turn or swivel, and thus adapt itself to the bevel, as indicated in Fig. 3, thus providing both a parallel and a swiveling vise-jaw by a very simple means.

15 It will be readily appreciated that by forming the vise-jaws with cylindrical stems and the clamp-plates with round bored sockets to receive them, not only is the attachment and removal of the vise-jaws rendered very simple 20 and secure, but the construction is such as can be made cheaply and yet accurately, for by ordinary operations of the machine shop it is very easy to bore the socket-holes *t* so that they shall be parallel with the clamping-faces 25 of the clamp-plates, and it is also easy to turn the cylindrical stems of the vise-jaws so that they shall be parallel with the clamping-faces of said jaws, so that accurate setting or parallelism of the parts is thus insured without 30 expensive work thereon, which is an important advantage. While, therefore, the aforesaid manner of engaging the vise-jaws with the clamp-jaws is very advantageous, and forms one feature of my improvement, yet I 35 do not, of course, confine myself to this special manner of engagement, for any suitable construction of the vise-jaws so as to be capable of being engaged with and disengaged from the clamp-plate may be adopted without desparting from the main feature of my invention.

40 It may also have been noted that I employ in this clamp a hand-wheel, *l*, for operating the screw, in lieu of the ordinary lever-handle, which is much preferable, as it is more convenient in affording an effective grasp to the 45 hand in any position, and in the fact that it is not liable to catch in the apron, as the lever-handle does; but I do not, of course, confine myself to the use of the hand-wheel.

From what has been already set forth, it will therefore be obvious that a bench-clamp formed as described and equipped with the separable vise-jaws shown forms a tool of much greater convenience and capacity for the shop than the common clamp, and at but a slight additional expense over the same, thereby presenting a valuable improvement in tools of this class.

What I claim is—

1. A combined bench clamp and vise, formed by the combination, with the clamp-plates *b c*, adapted to receive movable vise-jaws, of the separable vise-jaws *m m'*, adapted to be affixed to or removed from the upper edges of the clamp-plates, substantially as herein set forth. 60

2. The combination, with the clamp-plates *b c* of a bench-clamp, having sockets formed on or in the upper edge thereof, of the separable vise-jaws *m m'*, having bases seated upon the top edge of the plates, and projecting socket-stems entering said sockets, substantially as herein set forth. 70

3. In a combined bench clamp and vise substantially such as set forth, the clamp-plates *b c*, formed with vertical cylindrical sockets *t*, parallel with the clamping-faces of the plates, in combination with the separable vise-jaws *m m'*, formed with corresponding cylindrical shanks, *u*, parallel with their grasping-faces, to enter said sockets, substantially as and for the 80 purpose set forth. 75

4. The combination, in a clamp or vise such as set forth, with the clamp-plate *b*, having a socket, *t*, with notch *p*, of the separable vise-jaw *m*, having shank *u* and projection *o*, to 85 respectively enter said socket and notch, substantially as and for the purpose set forth.

5. The combination of the clamp-plates *b c*, connecting-screw *e*, separable vise-jaws *m m'*, and hand-wheel *l*, arranged and operating substantially as and for the purpose set forth. 90

CHARLES L. BELLAMY.
